FLOAT SWITCH

Joseph Paolini, Watertown, Mass.

Application April 24, 1934, Serial No. 722,172

1 Claim. (Cl. 200—84)

The invention relates to a signalling device and more especially a float switch for liquid fuel burning stoves.

The primary object of the invention is the provision of a switch of this character, wherein the liquid fuel as contained within a reservoir for consumption in the stove, on becoming low in said reservoir, will close a signal circuit and thus avoid the burners from becoming extinguished or other inconvenience in the use of the stove.

Another object of the invention is the provision of a device of this character, wherein the same is of novel construction so that it can be readily applied to and used in conjunction with the fuel supply of a liquid fuel burning stove and is automatic in the working thereof.

A further object of the invention is the provision of a device of this character which is extremely simple in construction, thoroughly reliable and efficient in its operation and purpose, durable, compact, and inexpensive to manufacture and install.

With these and other objects in view, the invention consists in the features of construction, combination and arrangement of parts as will be hereinafter more fully described in detail, illustrated in the accompanying drawings, which disclose the preferred embodiment of the invention, and pointed out in the claim hereunto appended.

In the accompanying drawings:

Figure 1 is a side elevation of a stove showing the device constructed in accordance with the invention applied thereto.

Figure 2 is a horizontal sectional view thereof.

Figure 3 is a vertical sectional view through the battery holder of the device.

Figure 4 is a fragmentary side elevation partly in section through the fuel reservoir.

Figure 5 is a fragmentary elevation of the connection between the float and the reservoir and the operating lever of the device, with the silencer in position to prevent the sounding of the alarm.

Similar reference characters indicate corresponding parts throughout the several views in the drawings.

Referring to the drawings in detail, A designates a vertical upright or post having the base B which may be supported upon a foundation, or otherwise. Adjustably carried by the post A is a liquid fuel feeding reservoir 10 having a removable cover 11 and this reservoir is formed with a clamp 12 which adjustably embraces the

post A for the mounting of said receptacle thereon.

Formed with the receptacle is a mouth piece 13 for a liquid fuel containing jar 14 removably fitted in a rack 15 which is adjustably clamped, 5 at 16, to the post A at the required distance above the reservoir 10 and the liquid fuel contained within the jar 14 is delivered into the said reservoir 10, as should be apparent.

Adapted to be located in the vicinity of the 10 post A is a burner stand 17 having twin burners 18, these being supplied with liquid fuel through the branches 19 of a feed pipe 20 connected with the reservoir 10, the feed of fuel to said burners 18 being controlled by a hand valve 15 21.

Carried by the post A is a dry cell battery box or holder 22 for accommodating a battery 23, this being arranged in a normally open electric circuit 24 including a bell signal or alarm 20 25, the latter being suitably supported by the box or holder 22. The circuit 24 is closed by a switch 26 included in said circuit and within the box or holder 22.

Located within the reservoir 10 is a float 27 25 having the stem 28 working through the top 11 of said reservoir and adjustably connected, at 29, with a vertically swinging lever 30 which is actuated for the closing of the switch 26 when the liquid fuel within the reservoir 10 is at a 30 determined low level. The lever 30 is swingingly mounted upon a pivot 31 on one of the brackets 32 for the carrying of the box or holder 22. It will be apparent that by the adjustment 29 the action of the float for the closing of the 35 switch 26 by the lever 30 with respect to the level of the liquid fuel within the reservoir 10 can be altered so as to have the alarm sounded at the time of the liquid fuel within the reservoir reaching a particular level.

Mounted upon the reservoir 10 is a silencer 40 for the alarm which comprises a pivoted lever 33, its end 34 working in the path of the lever 30, so that when the said lever 33 is thrown in one position it will lift the lever 30, whereby the 45 switch 26 will open so that the alarm will be silenced on the closing of said switch. The pivot 31 for the lever 30 is vertically adjustable in the bracket 32 in any suitable manner and shiftable in a slot in said bracket for the adjusting 50 medium.

In the operation of the device, it will be apparent that when the silencer, including the lever 33, is thrown to the dotted line position in Figure 4 of the drawings and the float 27 has 55

become lowered in conformity with the low level of fuel within the reservoir 10, the lever 30 will swing to close the switch 26 and thus the alarm 25 will be sounded, thereby indicating the condition of the fuel within the reservoir.

What is claimed is:

A float operated switch including a float stem, a switch operating lever pivotally mounted intermediate its ends and adjustably secured at 10 one end on the stem, the adjustably connected end of the lever being lowered by the stem to correspondingly raise the free end of the lever, a switch in the path of the free end of the lever adapted to be closed when the free end of the 15 lever is raised and adapted to be opened when

the free end is lowered, and means for manually raising the adjustably connected end of the lever and the float stem as a unit to lower the free end of the switch operating lever to open the switch comprising an angular lever pivoted at its elbow laterally of the stem and having one end disposed underneath the adjustably connected end of the switch operating lever, rocking of the angular lever on its pivot in one direction moving the free end of the lever upwardly into engagement with the adjustably connected end of the switch operating lever to raise the latter whereby to open the switch. 5 10
